TYPOGRAPHICAL SLUG CASTING MACHINE
AND MATRIX THEREFOR

Herbert Ellis, Shanghai, China, assignor to Linotype and Machinery Limited, London, England

Application August 18, 1938, Serial No. 225,526
In Great Britain April 21, 1938

17 Claims. (Cl. 199—47)

This invention relates to typographical slug casting machines and matrices therefor.

In preparing a slug or typebar in known machines molten metal is cast in a mould slot 5 pressed against the edges or faces of matrices composed in a line, the plane edge or face of each matrix having a recess, known as a routing notch, extending thereacross and a character indentation in the base of this recess. The mould lips 10 meet the plane surfaces of the matrices and clearly therefore the slug cast has on its surface a stepped portion formed in the matrix recesses and characters corresponding to the character indentations upstanding from the stepped portion. The cost and labour of manufacturing 15 matrices is increased by the existence of the above-mentioned recess in the base of which the character indentation is provided, and this is more especially true in respect of matrices of 20 large size and of matrices carrying characters in other than Arabic script.

As examples of cases in which such matrices are required there may be mentioned ideograph characters, such as used in Chinese and Japanese 25 printing, and decorations, such as employed in printing borders and the like. The casting of slugs from such matrices is not unusually effected by composing the matrix line by hand and subsequently presenting the line, with or without the 30 holder or stick in which it is composed, to a machine adapted to cast metal thereagainst. One such machine is well known under the registered trade-mark "Linotype" as an "all-purpose" machine, and the present invention is more 35 particularly, although not exclusively directed to the operation of machines of that kind and of matrices used therein.

It will be appreciated that in order for the line to be properly held and aligned in the machine 40 the over-all section or shape of the matrices or matrix line must be suitable to co-act with co-operating elements of the machine, and in fact there are known, for use in machines of the above-mentioned "all-purpose" kind matrices of 45 various shapes suitable therefor. All such matrices are open to the manufacturing disadvantage noted above that the character indentation is made in the base of a recess in the character-bearing face thereof.

The object of the present invention is to overcome these disadvantages, and with this end in view, according to the invention, a matrix character indentation is provided on a plane surface 50 rather than in a recess in the face, of a plate or block (which is preferably of simple geometric

form such as a cube or flat square plate), and this plate or block is adapted to co-act with another element so that the two together have an external shape or configuration suitable for use in the slug casting machine for which they are desired. 5 The element with which the matrix plate or block co-acts may be in the form of a holder of full-line length adapted to receive a plurality of such plates or blocks, and the final external cross-sectional shape or configuration resulting from 10 this assembly may be any of the known shapes used in casting machines of the character in question or of any other convenient shape, depending upon the form of casting machine being used. To facilitate assembly, the external element or holder may be formed of parts, separable or loosely interconnected but adapted to be pressed and/or locked together after insertion of the matrix plates or blocks; and mutually interlocking devices, such as co-acting tongues and 15 grooves, may be provided on the holder and the matrix plates or blocks. It will be noted that on account of the simple geometric form of the matrix plates or blocks they can be set in the external holder in either of two orientations, 20 each of which can be arrived at by turning the plate or block through 90° from the other orientation, the character remaining in its own plane during such turning. This possibility is of some 25 importance when the invention is used in connection with ideograph characters, such as Chinese characters, which may be desired in horizontal or vertical arrangement in the slug being cast. 30

The invention will be clearly understood from 35 the following description of one form (given, however, merely by way of example) which it may assume, and this description will be more readily followed by reference to the accompanying drawings, wherein:

Figure 1 represents a perspective view of a 40 holder for matrix blocks according to the invention;

Figures 2 and 3 represent respectively a back 45 elevation and a side sectional view of the holder shown in Figure 1, Figure 3 being a view along the line A—A of Figure 2;

Figures 4 and 5 represent respectively in perspective a spacer block and a matrix block for association, according to the invention, with the 50 holder shown in Figure 1 (Figure 5 being represented as a block carrying a Chinese character indentation);

Figure 6 represents an end view of the holder 55

shown in Figure 1 with a line of matrix blocks assembled therein:

Figures 7, 8 and 9 represent respectively a plan view, a longitudinal side view, and an end sectional view of a handstick suitable for carrying a holder such as shown in Figure 1, with a line of matrix blocks assembled therein (Figure 9 showing the holder and blocks in position); and

Figures 10 and 11 represent, in perspective, details of the invention.

In carrying the invention into effect in one convenient manner, shown in the accompanying drawings as suitable for use with a machine known, under the registered trade-mark "Lino-type", as an "all-purpose" machine, the general procedure in casting a slug may be similar to that described in the specification of U. S. A. Patent No. 2,023,557. The embodiment of the present invention now being referred to will be described 20 with reference to the casting of a slug containing Chinese characters in such a machine.

The character indentations are formed in any convenient way on the plane face of a square plate or block *a* (Figure 3), the sides of which 25 have grooves *b* extending round the periphery. A holder for a line of these matrix blocks *a* is shown in Figures 1, 2, 3 and 6, and is in the form of a substantially U-shaped channelled member, one of the side walls *c* being separate 30 from the L-shaped portion *d* formed by the base and the other side wall, but having lugs in the form of plates *e* secured thereto by screws *f* projecting from its bottom into guide grooves *g* in the outer surface of the base proper and these 35 lugs having pins *h* which engage with bridge pieces *i* screwed across the guiding grooves *g* to prevent separation of the parts. Compression springs *k* between the contiguous faces of these portions *c*, *d*, normally hold them apart to the 40 limit defined by the stopping pins *h* (thus temporarily widening the channel of the U-shaped holder), but the portions can be pressed together (and, if desired, held together by any suitable locking means such as a detent) when the 45 line of matrix blocks has been assembled in the holder. Ribs *l* are provided on the inner faces of the side walls of the holder to engage in the grooves *b* in the sides of the matrix blocks *a* when the holder portions are pressed together, 50 thus locating and holding the matrix blocks in position. The side walls of the holder are sufficiently deep to extend above the plane surfaces of the matrix blocks (as shown in Figure 6), and thus when a line is assembled they are equivalent 55 to the side walls of the recess or routing notch in a matrix of known shape with the character indented in the plane bottom face of the recess. Spacer members *m* (Figure 4) for closing the ends of a line may be similar to matrix blocks 60 but are deeper so that their upper surfaces (which do not, of course, carry a character indentation), when they are assembled, lie flush with the upper faces of the side walls of the holder. The spacers may be grooved on only two opposite 65 sides, as shown in Figure 4, instead of on all four sides which is the case for the matrix blocks when carrying Chinese characters (Figure 5).

Externally the holder may be of such shape (as shown in Figure 6), that when the matrices are 70 assembled therein the cross-section of the whole is identical with that of a known matrix, such as that shown in Figure 9 of specification No. 2,023,557. This external shape is of importance only insofar as it is required in the machine in 75 which the slug is being cast and may, therefore,

vary to many other shapes, e. g., that shown in Figure 9 of the above-mentioned specification No. 2,023,557. It will be noted that on account of the side groove *b* for locating the matrix blocks in the holder extending fully round the periphery, 5 the blocks can be assembled side-by-side in either of two orientations corresponding to their relative vertical or horizontal positions on the cast slug. This is a matter of some importance 10 in casting slugs from ideograph character matrices, such as Chinese.

When a line of matrices and spacers has been assembled by placing them directly in the holder and thereafter pressing the holder portions together in the manner described above, the whole 15 may be presented directly to the machine (if the machine is such as to deal directly with an assembled matrix line) or it may be placed in a handstick. Conveniently the form of handstick employed, if the slug is being cast in a "Lino-type" all-purpose machine, may be that shown 20 in Figures 7 to 9 herewith corresponding to Figures 13 and 14 of specification No. 2,023,557, the holder carrying the assembled line of matrix blocks being adapted to fit into the stick 25 in place of the matrices therein shown, and the matrix blocks and holder being longitudinally clamped by the screw clamping plate *n* illustrated herein. The stick is thereafter presented to the machine in known manner. It will be understood 30 that any other convenient form of handstick may be employed according to the cross-section of the holder and to the kind of machine being used.

In order to facilitate removal of the holder and 35 matrices from the stick after casting two apertures *o* may be provided through the base of the stick, and there may be provided on the machine, e. g., by screwing a plate *p* (Figure 10) thereon, two studs *r* (which may have rubber or fibre 40 head portions, as shown) spaced to correspond to the apertures in the stick. Upstanding plates *s* may be provided adjacent to these studs so that by holding the handstick with its edges against these plates the apertures *o* stand over the studs 45 *r* and a downward movement of the stick (the clamping plate *n* thereof being released) results in ejection of the holder.

In order to facilitate the assembling of the 50 matrix blocks *a* loosely in the holder before the latter is closed, a tray-like member *t* (Figure 11) may be employed, comprising a base substantially of the same size and shape as holder, having two upstanding contiguous side walls. This 55 is conveniently held in the hand, with the matrix holder therein, during assembly, the upstanding end wall *u* preventing the loosely inserted matrix blocks from sliding out.

It should be understood that the invention is not restricted to the arrangement in which matrix blocks can only be assembled as a line, but can as readily be employed for casting a slug from one, or from a small number of matrix blocks. Further the invention is not restricted to matrix blocks with ideograph or other characters, 65 but may be employed with matrices having any kind of character thereon, and not necessarily capable of being set in either of two orientations. Moreover, there is not excluded from the invention any arrangement in which the matrix blocks 70 are assembled other than by hand. These and any other modifications of the invention, which become desirable in order to carry the invention into effect under different conditions and requirements which have to be fulfilled, may be 75

adopted without departing in any way from the scope of the invention.

Having described my invention I declare that what I claim and desire to secure by Letters Patent is:

- 5 1. In or for a typographical slug casting machine a matrix in the form of an element having a plane face and a character indentation on said plane face, in combination with a holder therefor having a casting face set forward with reference to said plane character-bearing face. 5
- 10 2. In or for a typographical slug casting machine a matrix in the form of a block of simple geometric shape having a plane face, a character indentation on said plane face, and grooves in at least two opposite side faces of the block, in combination with a holder therefor having ribs seated in said grooves and having a casting face set forward with reference to said plane character-bearing face. 10
- 15 3. In or for a typographical slug casting machine a matrix in the form of a cuboidal block having a character indentation upon a plane face thereof and a groove extending fully round the side faces adjacent to said plane, character-bearing face of the block. 15
- 20 4. In or for a typographical slug casting machine a matrix in the form of an element having a character indentation on one face thereof and so shaped that it can be associated with adjacent matrices, to form a matrix line, in either of two orientations distinguished from one another by 90° rotational displacement about an axis perpendicular to the character-bearing face of the element. 20
- 25 5. In or for a typographical slug casting machine a matrix according to claim 4 provided with co-acting means for engagement in a matrix holder which permit engagement in either of the two specified orientations. 25
- 30 6. In or for a typographical slug casting machine a matrix in the form of an element having a plane face with a character indentation thereon, in combination with a holder therefor shaped externally to co-act with the normal line holding and locating members of the machine. 30
- 35 7. In or for a typographical slug casting machine a matrix holder comprising a substantially U-shaped member adapted to hold between its parallel limbs a matrix in the form of an element having a plane face with a character indentation thereon. 35
- 40 8. In or for a typographical slug casting machine a matrix holder comprising a substantially U-shaped member the parallel limbs of which are movable towards and away from one another, and are formed with elements constituting part of an interlocking connection between said holder and a matrix element insertable therein between the parallel limbs. 40
- 45 9. A matrix holder according to claim 8 wherein the upstanding limbs of the U-shaped member are urged apart by spring means to the limit determined by stop means in the mutually engaging parts associated with said limbs. 5
- 50 10. A matrix holder according to claim 8 wherein said limbs comprise each a tongue or rib projecting into the channel between the limbs and adapted to engage corresponding grooves in a matrix block assembled in the holder. 10
- 55 11. In or for a typographical slug casting machine the combination of a matrix block having a plane face with a character indentation thereon, and a holder therefor, of such shape in cross-section that the cross-section of the combination is substantially identical with the cross-section of a normal matrix suitable for the machine in question. 15
- 60 12. In or for a typographical slug casting machine a plurality of matrix blocks, a holder therefor, and a handstick adapted to receive and clamp said holder with the blocks therein. 20
- 65 13. For use in the combination claimed in claim 12 a handstick having an aperture in the base thereof to facilitate ejection of said holder after a slug has been cast. 25
- 70 14. For use in the combination claimed in claim 12 a handstick having an aperture in the base thereof to facilitate ejection of said holder after a slug has been cast, a projection on the machine and means such as upstanding plates arranged adjacent to said projection to facilitate location of the handstick in such a position that said aperture is in register with said projection. 30
- 75 15. For use in assembling matrix elements, in a holder according to claim 7, a tray-like support having an upstanding edge adapted to prevent the elements from dropping out of one end of the U-shaped holder during assembly. 35
- 80 16. In or for a typographical slug casting machine, a matrix holder formed in its casting face with a groove or recess, and a matrix element arranged in said groove or recess and having a plane casting face set back with reference to the casting face of the holder, said element having a character indentation on said plane casting face. 40
- 85 17. In or for a typographical slug casting machine, an elongated matrix holder formed in its casting face with a longitudinal groove or recess, and a series of flat plates arranged in said recess in edge to edge contact, certain of said plates having plane casting faces set back with reference to the casting face of the holder with character indentations on said plane casting faces, and other of said plates having plane casting faces without character indentations arranged flush with the casting face of the holder. 45

HERBERT ELLIS. 60
